UNITED STATES PATENT OFFICE

2,066,373

LOCKSTITCH SEWING MACHINE

Laurence E. Topham, Wenham, Mass., assignor to
 United Shoe Machinery Corporation, Paterson,
 N. J., a corporation of New Jersey

Original application March 23, 1932, Serial No.
 600,654. Divided and this application June 8,
 1934, Serial No. 729,617. Renewed March 10,
 1936

15 Claims. (Cl. 112—57)

The present invention relates to shoe sewing machines which employ a hook needle to draw loops of needle thread through the work, and is herein illustrated as embodied in a machine of 5
 5 the McKay type such as that disclosed in the patent to Ashworth No. 1,914,936 granted June 20, 1933.

The object of the invention is to improve the 10 operation of shoe sewing machines, and more particularly to provide improved devices for insuring proper formation and setting of each 15 stitch at a uniform distance within the work during sewing and, when employed in a lockstitch machine, for causing the final stitch to remain above the surface of the work where the threads 20 may be severed simultaneously.

In the machine herein illustrated the stitch is drawn down and set by the needle thread take-up and a feature of the invention is embodied in 25 20 a construction utilizing a thread lock for gripping the thread between the take-up and the thread supply, as the take-up completes its thread drawing stroke, and after a supply of thread has been drawn through the tension for 25 the next stitch.

In lockstitch shoe sewing machines of ordinary 30 construction, it has been found desirable to permit the last formed needle loop at the end of the seam to remain above the surface of the work as 35 the machine is stopped, where the needle loop, together with the locking thread, may readily be severed by a single cutting stroke. In order to insure that a definite amount of thread will remain above the surface of the work, according 40 to another feature of the present invention, a second thread lock is arranged between the take-up and the work for gripping the thread and positively preventing the take-up from setting 45 the final stitch.

40 Other features of the invention includes the devices, combinations and arrangements of parts hereinafter described and claimed, certain of which, while adapted for use in sole sewing machines of the McKay type, are also capable of 45 use with other types of sewing machines.

The several features of the present invention and the advantages obtained thereby will be readily understood by those skilled in the art from the following description taken in connection with the accompanying drawings which 50 illustrate an embodiment of the invention.

In the drawings, Fig. 1 is a view in side elevation of the complete machine; Fig. 2 is a view in front elevation, partly in section, showing the 55 take-up mechanism and thread clamps for the

needle thread of the machine shown in Fig. 1; Fig. 3 is a view in side elevation of the take-up mechanism and thread clamps shown in Fig. 2, a part of the casing and the wax pot being shown in section; Fig. 4 is a sectional plan view on an enlarged scale, of the thread locks and a portion 5 of the mechanism for operating them in positions assumed on stopping the machine; Fig. 5 is a detail view of a part of the mechanism shown in Fig. 4, looking from the left; Fig. 6 is a detail 10 view of a part of the mechanism shown in Fig. 4 looking from the right; Figs. 7 and 8 are fragmentary views of portions of the thread lock operating mechanisms taken along the line 7—7 of Fig. 4, and illustrating successive stages of 15 operation; Fig. 9 is a sectional view taken on the line 9—9 of Fig. 1, looking from the front of the machine; Fig. 10 is a diagrammatic view showing the relative relations of the take-up and the thread locks during the sewing operation 20 while the needle loop is passing over the shuttle; Fig. 11 is a similar view showing the parts as the 25 stitch is being set; and Fig. 12 is a view showing the same parts just before the machine stops with thread of the final stitch not drawn into the 25 work.

The lockstitch shoe sewing machine herein illustrated is similar to that disclosed in the application of the present inventor, Serial No. 600,654, filed March 23, 1932 of which the present application is a division. A great many of 30 the parts common to the two machines are illustrated in the accompanying drawings, but inasmuch as they are fully illustrated and described in the above application, they will be only briefly 35 referred to in the following description.

The illustrated machine is driven from an electric motor 12 through a clutch mechanism indicated in Fig. 1 in dotted lines. This clutch mechanism is controlled from a foot treadle 14 40 which is normally held in raised position by means of a spring 16. The clutch mechanism acts to connect and disconnect the motor with a shaft 18 and a sleeve 20 in the base of the machine, from which motion is transmitted to a 45 vertical shaft 22 extending up to the sewing head of the machine. Rotation of the shaft 22 imparts a corresponding movement to a sewing shaft 24 for operating the needle, shuttle and other related parts.

The shoe to be operated upon is supported on an angular horn 26 having an inclined upper portion enclosing needle threading devices. Motion is imparted to the needle threading devices through a hollow vertical shaft 28 connected 50 55

through suitable gears to a horizontal shaft 30 and the vertical shaft 22 driven from the motor 12.

The sewing head of the machine is provided with a straight hook needle 32, a presser foot 34, a loop taker in the form of a shuttle 36, to carry the needle loop over the bobbin or locking thread, a feed point 38, a take-up 40, a needle looper 42 and a thread finger 44, the latter of which is mounted in the horn. The upper end of the horn is constructed with the usual needle opening to permit the needle to enter the horn in receiving the thread from the looper.

The horn 26 is mounted on the machine to rotate a complete turn of 360 degrees, and is provided with a downwardly extending hollow spindle having bearings between the upper and lower ends of the spindle and the frame of the machine. The shaft 28 is journaled within the spindle of 10 the horn to rotate about an axis concentric with the axis of rotation of the horn, which coincides with the longitudinal axis of the needle.

A feature of the present invention relates to a thread lock for gripping the thread to set the 15 stitch uniformly through the action of the take-up 40. The thread lock and take-up are illustrated in Figures 2 and 3 in which the thread lock, hereinafter referred to as the sewing thread lock, is indicated at 46. The needle thread 47 passes from a source of supply 48, and through a 20 tension device 50 of ordinary construction provided with an adjustable tension nut 52 for varying the amount of tension, thence around a shaft 54 carrying the thread lock 46 loosely journaled 25 in a bracket 56 attached to the machine, downwardly through a wax pot 58 of ordinary construction, upwardly over a pulley 60 carried by the bracket 56, downwardly around a pulley 62 at the end of the take-up lever 40 through a pulley 64 on the bracket 56, and upwardly into the 30 horn. In order to prevent entanglement of the thread about the end of the take-up lever, the pivot about which the pulley 62 at the end of the take-up rotates is provided with an elongated 35 spindle 66 (see Fig. 3) extending from the axis of the pulley at right angles to the line of movement of the take-up. The take-up 40 is operated from a cam 68 carried by the horizontal shaft 30 which forms a part of the operating connections to the needle threading devices in the horn. The take-up is fulcrumed on a shaft 70 provided 40 with a headed portion and secured on a bracket 72 attached to the machine frame. Thread drawing and surrendering movements are imparted 45 to the take-up through connections between the take-up and a cam slot 74 formed in the cam 68, which connections include a bell-crank 75 formed with a sleeve portion 78 fulcrumed on a shaft 80 secured to the frame of the machine, and a link 82 connected between the take-up lever and one 50 end of the bell crank. The other end of the bell-crank carries a cam roll 84 engaging the cam slot 74. One end of the link 82 is directly pivoted to the take-up lever 40, and the other 55 end is loosely pivoted on a stud 86 clamped within an adjusting slot in the bell-crank. The sleeve 78 of the bell-crank is loosely mounted on the shaft 80, and is prevented from displacement by a collar 88 clamped at the end of the shaft.

The thread lock 46 is actuated to grip the 60 thread between the take-up and the supply during each thread drawing stroke of the take-up as it reaches the lower portion of its stroke. The thread tension 50 offers sufficient resistance to cause the take-up, in moving from the position

indicated in Figs. 2 and 10, to draw loop of needle thread from the shuttle toward the work. As the needle loop approaches the work, it engages the locking thread, indicated at 90, and draws it against the work. Thereafter, the resistance offered by contact of the thread with the work exceeds the resistance offered by the thread tension, so that a supply of thread is drawn through the tension before the take-up reaches the end of its thread drawing stroke. Just before the 10 end of the take-up stroke is reached, the thread lock 46 is applied, and further movement of the take-up draws the needle loop a uniform distance into the work against the thread lock 46, as shown in Fig. 11. Thus, the three operations of drawing the needle loop against the work, measuring thread from the supply, and setting the stitch, are accomplished during a single stroke of the take-up.

The thread lock 46 is actuated to grip the 20 thread just before the needle thread take-up 40 reaches the end of its thread drawing stroke by a cup-shaped cam 92, shown in Figs. 2 and 4 25 adjustably secured in a recess in the cam 68 by a set screw 94, and connections actuated by the cam comprising a lever 96 having a cam roll 98 at one end arranged to engage the cam 92, the shaft 54 which supports the thread lock 46, a spring 100 surrounding the shaft and a block 102 secured to the shaft 54 by a set screw 104 (see 30 Fig. 4). The thread lock 46 is formed as a washer movable toward and from a shoulder 106 formed on a sleeve 108 surrounding the shaft 54 and loosely fitting within an opening in the bracket 56. The shaft 54 is mounted in the 35 bracket 56 to both oscillate and move freely in a longitudinal direction. The lever 96 is clamped by means of a bolt 110 to the shaft 54 to oscillate the shaft when the cam roll 98 is engaged by the cam 92. The block 102 is provided with a pair of 40 projections 112 to cooperate with similarly shaped recesses 114 contained in a block 116 mounted on the bracket 56 and is resiliently pressed by the spring 100 compressed between the block 102 on the shaft 54 and a washer 118 45 thrusting against the bracket 56 to cause the thread lock 46 to grip the thread against the shoulder 106. As the shaft 54 is oscillated by the cam 92, the projections 112 rise part way out of the recesses 114, moving the shaft 54 longitudinally to release the thread at the proper time to allow the take-up to measure thread during its thread drawing stroke. The cam 92 is so proportioned that the time in which the cam roll 98 is released to move under the action of the spring 50 100 and the projections 112 enter the recesses 114 occurs just before the take-up has completed its stroke. In order to adjust the timing, the block 116 (see Fig. 5) is adjustably secured to the bracket 56 by a bolt 120 slidably arranged in a 55 slot 122 in the bracket.

In accordance with another feature of the invention, in order to simplify the act of severing the thread at the end of a seam, the loop of needle thread of the final stitch is positively prevented from being drawn into the work and is held in a position shown in Fig. 12, through the action of a second thread lock in the form of a washer 124, hereinafter referred to as the final 60 stitch thread lock. This second thread lock comprises the washer mounted loosely on a shaft 126 to be moved, in gripping the thread, toward and from a shouldered sleeve 128 surrounding the shaft. The sleeve 128 is loose on the shaft 126 and slides freely in a longitudinal direction 70 75

in an opening in the bracket 56 but is held against angular rotation by a pin 130 projecting from the bracket 56, and passing through a slot-projection at one side of the sleeve 128.

5 In order to operate the second thread lock 124 effectively to grip the thread, it must act during the thread drawing stroke of the take-up 40, and for this purpose the shaft 126 is operated by a cam 132 secured to the end of the shaft 30. The 10 shaft 126 carries an arm 134 fixed to its inner end which is provided with a cam roll 136 in position to be acted upon by the cam 132. The shaft 126 is loosely mounted in the bracket 56, and is moved longitudinally by the action of a 15 spring 138 surrounding the central part of the shaft. The spring is compressed between a block 140 clamped by a set screw 144 to the shaft and a washer 146 thrusting against the bracket 56. The block 140 is provided with a pair of 20 projections 148 cooperating with similarly shaped recesses 150 in a block 152 secured to the bracket 56, to impart a longitudinal movement against the action of the spring 138 as the shaft is oscillated by the cam 132. This longitudinal movement causes the thread lock 124 to move toward and from the sleeve 128 to grip the thread in 25 timed relation with the operation of the take-up. The thread lock thus operates to grip the thread between the take-up and the work as the thread 30 is being drawn toward the work by the take-up, preventing the take-up from drawing the last formed needle thread loop and the locking thread against the work. To adjust the timing of the 35 second thread lock, the block 152 is adjustably secured to the bracket 56 (see Fig. 6) by a bolt 154 passing through a slot in the bracket.

In order to prevent the thread lock 124 from acting to grip the needle thread during each 40 stitch-forming cycle of the machine, the sleeve 128 is provided with a pair of diametrically opposite recesses 156 to cooperate with projections 158 formed on a collar 160. The collar 160 is 45 loosely mounted on the sleeve 128, and is provided with gear teeth 162 (see Fig. 2) meshing with a segmental gear 164 extending from the hub of a lever 166 loosely mounted on the sleeve 168. During normal operation of the machine, the collar 160 assumes a position different from that shown in Fig. 4, and in which the projections 158 coincide with the recesses 156 on the 50 shouldered sleeve 128, so that the space between the thread lock washer 124 and the shoulder of the sleeve is greater than the thickness of the thread. As a result, the thread is free of a 55 lock at all times during the sewing of a seam. As the machine is brought to rest, the projections 158 are moved out of the recesses 156 to the positions shown in Fig. 4, and the thread is gripped by the thread lock, permitting 60 the needle loop to remain above the surface of the work, as in Fig. 12.

It is necessary during the time in which the 65 final stitch thread lock 124 acts, to prevent the application of the sewing thread lock 46, as otherwise the thread would be broken by the take-up. For this purpose, connections operated during the completion of the final stitch as the machine is brought to rest, operate to release the 70 sewing thread lock 46 from engagement with the shoulder 106, and permit the application of the final stitch thread lock 124, and finally to release the thread lock 124 from the sleeve 128, simultaneously with the release of the needle thread tension, so that the work may be withdrawn a short distance from the machine be-

fore severing the thread. These connections for actuating the thread locks in their proper sequence during the completion of the final stitch are operated by a stop mechanism which is of substantially the same construction as that described in Patent No. 1,874,690 granted August 30, 1932 to Ashworth. 5

The stop mechanism which is rendered operative when it is desired to bring the machine to rest acts to disconnect the needle from its 10 actuating mechanism and lock it out of operation at the top of the retracting stroke and to raise the presser foot from engagement with the work as well as to actuate the thread locks and tension device in the manner just indicated. 15 When the foot treadle 14 is released, a horizontal shaft 168 in the sewing head (see Figs. 1 and 9), is rotated in a clockwise direction. The shaft 168 is journaled in the machine frame and carries at one end an arm 170 loosely mounted 20 thereon. Secured to the said end of the shaft is an arm 172 connected to the treadle 14 by a link 174. This arm is provided with a projection 176 extending beneath a rearward extension of the arm 170 and engaging said rearward extension 25 upon the release of the treadle. The arm 170 is connected to a shaft 178 by a link 180 connected to the arm 170 at one end and at the other end to an arm 182 fixed to the shaft 178. Release of the foot treadle also acts to swing 30 an arm 184 attached at the rearward end of the shaft 178 in a counter-clockwise direction as viewed in Fig. 9. The arm 184 extends downwardly, and loosely supports a pin 185 at its lower end. The pin 185 is connected to the ends of a 35 pair of links 186 and 187 which, in turn, are connected to a lifting member 188 and a retaining member 189, respectively, loosely suspended at their upper ends from the sewing shaft 24. The member 189 is provided with an eccentric 40 strap 190 surrounding an eccentric member 191 on the sewing shaft 24, but the hook member 188 is supported loosely on the shaft itself, so that no movement is imparted to it by rotation of the shaft. When the shaft 178 is rocked by 45 releasing the foot treadle at the end of a seam, the lifting member 189 is moved toward the right by the arm 184 against one arm of a T-shaped lug 192 projecting laterally from an arm of a lever 193 loosely mounted on a shaft 194 mounted in the machine frame. The shaft 194, being 50 rotatably mounted, is provided at its rearward end with an arm 195 secured to the shaft and arranged with a portion 196 overlying the lug 192. This movement, of course, occurs only 55 after the motor has been disconnected from the machine, the sewing shaft continuing to rotate under the momentum of the rotating parts. As the shaft continues to turn, the hook 189 is forced beneath the lug 192 by a spring 197 surrounding the link 187. When the lever 193 is 60 actuated, an outwardly extending arm thereon is moved downwardly to operate the thread locks 46 and 124 through a second lever 198 (see Fig. 1) and a link 199 connecting the two levers. 65 The lever 198 is fulcrumed on a bolt 200 threaded into the frame of the machine, and is formed with openings 201 and 202 for engagement with enlargements 203 and 204, respectively (see Fig. 4) formed at the ends of the levers 96 and 166, 70 in the order stated, for operating the thread locks. The lever 198 is maintained in a position in which the sewing thread lock acts to grip the thread by a spring 205 connected to the machine frame, and the lever carries a pair of set screws 75

206 and 207 entering within the opening 201 to adjust the relative movement between the lever 198 and the sewing thread lock lever 96.

- As the stop mechanism begins its operation, lever 193 (see Fig. 9) in the head of the machine begins its movement and the sewing thread lock operating lever 96 is rocked with the shaft 54 to release the sewing thread lock 46. This movement also moves the lever 166, rotating the projections 158 out of the recesses 156, so that as the take-up draws the final needle loop towards the work, the thread lock 124 will be operated to grip the thread, and the thread lock 46 will be held in released position. The position 15 of the lever 96 under these circumstances is shown in Fig. 7, in which the adjusting screw 207 is shown as rocking the lever 96 to a position in which the sewing thread lock 46 is released.
- 20 In order to release the final stitch thread lock 124 as the main sewing shaft 24 continues to rotate, the lever 96 is rocked into the position shown in Fig. 8, and a lug 208 formed on the lever 96 engages a finger 209 on the arm 134, causing the arm 134 to be operated away from a position in which the final stitch thread lock 124 grips the thread. At the same time that the thread locks are released, the tension on the thread is also released by a downwardly extending arm of the lever 198 (see Fig. 1) and a rod 210 pivotally connected to the arm of the lever. The forward end of the rod carries a perforated enlargement 212 which bears against the tension 50, and guides the thread between the tension and the supply. At the end of the stop mechanism operation, the lever 198 is moved and the rod 210 releases the thread from the tension, so that the work may be withdrawn from the machine without resistance.
- 40 The parts thus operated are retained in position by the action of the retaining member 189 engaging the lug 192 and the spring 197 which surrounds the link 187 acting to prevent release of the retaining member 189 when the sewing shaft is brought to rest and until the treadle 14 is again depressed.

As the machine is started by movement of the treadle 14, the shaft 168 is rocked in a reverse direction, and the retaining member 189 is released from the lug 192 against the action of the spring 197, by an arm 214 carrying a roll fixed to the shaft 168 and engaging a cam surface on the retaining member 189. The lifting member 188 is also retracted from engagement 55 with the lug 192 by movement of the arm 182 on the shaft 176 as the treadle is depressed.

The nature and scope of the invention having been indicated, and an embodiment of the invention having been specifically described, what is claimed is:

1. A lockstitch sewing machine having, in combination, stitch-forming devices including a hook needle, a thread tension, a looper, a take-up acting to draw down a loop of needle thread against the tension until the resistance offered by contact of the loop with the work exceeds the amount of tension and thereafter to draw the thread through the tension from the supply for the next stitch, and a thread lock for gripping the thread between the take-up and the supply while the take-up completes its stroke to set the stitch.
2. A lockstitch sewing machine having, in combination, stitch-forming devices including a hook needle, a thread tension, a looper, a take-up acting to draw down a loop of needle thread against

the tension until the resistance offered by contact of the loop with the work exceeds the amount of tension and thereafter to draw the thread through the tension from the supply for the next 5 stitch, and a thread lock arranged between the take-up and the thread tension for gripping the thread between the take-up and the supply while the take-up completes its thread drawing stroke and for retaining its grip on the thread as the take-up yields up thread to the other stitch-forming devices.

3. A lockstitch sewing machine having, in combination, stitch-forming devices including a hook needle, a looper, a loop taker and a take-up, mechanism for stopping the operation of the machine with the needle disengaged from the work, and a thread lock arranged between the take-up and the work to grip the thread and prevent the take-up from drawing the last formed loop of needle thread together with the locking thread 20 against the work.

4. A lockstitch sewing machine having, in combination, stitch-forming devices including a hook needle, a looper, a loop taker and a take-up, mechanism for stopping the operation of the machine with the needle disengaged from the work, a thread lock arranged between the take-up and the work, and normally inactive mechanism rendered active in stopping the machine for actuating the thread lock to grip the thread 30 and prevent the take-up from drawing the last formed loop of needle thread together with the locking thread against the work.

5. A lockstitch sewing machine having, in combination, stitch-forming devices including a hook 35 needle, a looper, a loop taker, a take-up, a sewing shaft and suitable connections for actuating the stitch-forming devices, means for driving the sewing shaft, means for disconnecting the sewing shaft from its driving means and for rendering 40 inoperative the actuating connections between the needle and shaft while the needle is at the limit of a loop drawing stroke, a thread lock arranged between the take-up and the work and normally inactive mechanism rendered active in 45 stopping the machine for actuating the thread lock to grip the thread and prevent the take-up from drawing the last formed loop of needle thread together with the locking thread against the work.

6. A lockstitch sewing machine having, in combination, stitch-forming devices including a hook needle, a looper, a loop taker and a take-up, mechanism for stopping the operation of the machine with the needle disengaged from the work, a thread lock arranged between the take-up and the work, normally inactive mechanism rendered active in stopping the machine for 55 actuating the thread lock to grip the thread and prevent the take-up from drawing the last formed loop of needle thread together with the locking thread against the work and thereafter to release the thread from the grip of the thread lock.

7. A lockstitch sewing machine having, in combination, stitch-forming devices including a hook 65 needle, a looper, a loop taker and a take-up, mechanism for stopping the operation of the machine with the needle disengaged from the work, a thread lock arranged between the take-up and the work, a cam for actuating the thread lock to grip the thread and prevent the take-up 70 from drawing a loop of needle thread together with the locking thread against the work as the take-up completes its thread drawing stroke, and normally inactive mechanism for preventing the

thread lock from gripping the thread during sewing of a seam, said mechanism being rendered active during stopping of the machine for permitting the thread lock to grip the thread 5 under the action of the cam and thereafter for releasing the thread from the grip of said thread lock.

8. A lockstitch sewing machine having, in combination, stitch-forming devices including a hook 10 needle, a looper, a loop taker, a take-up and a thread lock arranged between the take-up and the supply of thread acting intermittently during sewing to grip the thread as each stitch is set, a second thread lock arranged between the take-up 15 and the work to grip the thread and prevent the take-up from drawing the last formed loop of needle thread together with the locking thread against the work, and means for releasing the thread from the thread lock on the supply side of the take-up as the second thread lock is actuated to grip the thread on the work side of the take-up.

9. A lockstitch sewing machine having, in combination, stitch-forming devices including a hook 20 needle, a looper, a loop taker, a take-up, a thread lock arranged between the take-up and the supply of thread, a sewing shaft and suitable connections for actuating the stitch-forming devices comprising a cam shaft for actuating the thread lock intermittently during sewing to grip the 25 thread as each stitch is set, a second thread lock actuated by the cam shaft to grip the thread between the take-up and the work and prevent the take-up from drawing a loop of needle thread together with the locking thread against the work, 30 and normally inactive mechanism for preventing the second thread lock from gripping the thread during sewing of a seam, said mechanism being rendered active during stopping of the machine for permitting the second thread lock to grip the 35 thread under the action of the cam shaft and thereafter for releasing the thread from the grip of said thread lock.

10. A lockstitch sewing machine having, in combination, stitch-forming devices including a 40 hook needle, a looper, a loop taker, a take-up, a thread lock arranged between the take-up and the supply of thread, a sewing shaft and suitable connections for actuating the stitch-forming devices comprising a cam shaft for actuating the 45 thread lock intermittently during sewing to grip the thread as each stitch is set, a second thread lock actuated by the cam shaft to grip the thread between the take-up and the work and prevent the take-up from drawing a loop of needle thread 50 together with the locking thread against the work, normally inactive mechanism for preventing the second thread lock from gripping the thread during sewing of a seam, said mechanism being rendered active during stopping of the machine for 55 permitting the thread lock to grip the thread under the action of the cam shaft, and means for releasing the thread from the thread lock on the supply side of the take-up as the second 60

thread lock is actuated to grip the thread on the work side of the take-up.

11. A sewing machine having, in combination, 5 stitch-forming devices including a hook needle and a pivoted take-up lever for surrendering thread as the needle is retracted from the work and for pulling the thread through the work after the thread is released from the needle, a pulley 10 on the take-up, and an elongated spindle extending from the center of the pulley perpendicular to the line of movement of the take-up for preventing entanglement of the thread about the free end of the take-up.

12. A sewing machine having, in combination, 15 stitch-forming devices including a hook needle and a pivoted take-up lever for surrendering thread as the needle is retracted from the work and for pulling the thread through the work after the thread is released from the needle, a pulley 20 on the take-up, and an elongated spindle extending at right angles to the line of movement from the take-up for preventing entanglement of the thread about the free end of the take-up.

13. A lockstitch shoe sewing machine having, 25 in combination, stitch forming devices including a hook needle, a take-up for yielding up and withdrawing thread from the other stitch forming devices, a thread supply, a thread lock acting between the take-up and the supply to grip the thread as each stitch is being set, and means for 30 actuating the take-up while the thread is released from the lock to cause a length of thread sufficient for the succeeding stitch to be drawn from the supply, and thereafter to set the stitch while the 35 length of thread for the succeeding stitch remains between the thread lock and the work.

14. A lockstitch shoe sewing machine having, 40 in combination, stitch forming devices including a hook needle, a take-up for drawing the needle loop down to the work and for setting the stitch at the end of its loop drawing stroke, a thread 45 lock against which the stitches are set, and means for actuating the take-up and thread lock to draw thread through the lock between the time when the needle loop is drawn down and the time the stitch is set.

15. A lockstitch sewing machine having, in combination, stitch-forming devices including a hook needle, a thread tension, a looper, a take-up 50 acting to draw down a loop of needle thread against the tension until the resistance offered by contact of the loop with the work exceeds the amount of tension and thereafter to draw the thread through the tension from the supply for the next stitch, a thread lock for gripping 55 the thread between the take-up and the supply while the take-up completes its stroke to set the stitch, and normally inactive mechanism rendered active in stopping the machine for preventing actuation of the thread lock during formation of the last stitch.

LAURENCE E. TOPHAM.
